CLAIM

The ornamental design for a surfboard holder for vehicle, as shown and described.

DESCRIPTION

FIG. 1 is a front isometric view of the surfboard holder for vehicle of the present invention;

FIG. 2 is a front view of the invention of FIG. 1;

FIG. 3 is a back view of the invention of FIG. 1;

FIG. 4 is a side view of the invention of FIG. 1, as seen from the left side of FIG. 2;

FIG. 5 is a side view of the invention of FIG. 1, as seen from the right side of FIG. 2;

FIG. 6 is a top plan view of the invention of FIG. 1; and, FIG. 7 is an exemplary perspective view of the invention of FIG. 1 being used in conjunction with additional holders to secure a surfboard on a vehicle.

The broken lines on FIG. 7 form no part of the claimed design.
